TOILET SEAT COVER DISPENSER

Nuta Zajfman, New York, N.Y.

Application August 17, 1955, Serial No. 528,948

1 Claim. (Cl. 225—47)

This invention relates to improvements in sanitary devices, and washroom accessories and the like.

An object of the invention is to provide a novel and improved device whereby as needed, there is dispensed from the device a toilet seat covering means shaped to overlie the seat portion of a toilet seat, so that the same is covered, and bodily direct contact with the toilet seat is avoided.

Another object of the invention is to provide a novel and improved device in which there is a plurality of toilet seat covers arranged sequentially, one of which at a time may be dispensed from the device, which is disposed in close proximity to a toilet seat, for covering the same, with convenient means for detaching the dispensed toilet seat cover from the undispensed ones remaining in the device, whereby the same may be employed in covering the tangible portions of the toilet seat to avoid direct bodily contact therewith.

A further object of the invention is to provide a novel and improved toilet seat cover dispensing device in which there is a housing provided with a bar or shaft for extending through the hollow hub of a roll of toilet seat covers in rolled up disposition, the housing having a discharge opening through which the end of the roll of toilet seat covers is extensible for pulling the same out sequentially, and including novel releasable locking means for normally engaging said roll against pulling out, until needed, and novel cutting off means for cutting off or detaching a pulled out section of the roll, forming a single unitary toilet seat cover for overlying the tangible portions of a toilet seat.

Still a further object of the invention is to provide a novel and improved toilet seat cover dispensing device which has a housing mountable either upon the toilet tank directly, or upon a wall adjoining the toilet bowl, and within easy reaching access when in use, from either side thereof.

Still another object of the invention is to provide a novel and improved toilet seat cover dispensing device, in which there is a toothed means normally engaged with a row of openings formed in and along the roll of toilet seat covers in the housing, so as to block undesired pulling out of a toilet seat cover, and in which said toothed engaging means may be pressed or moved to a position at which it is unlocked, and allows a seat cover to be pulled out or dispensed, whereupon it returns to locking position.

Another object of the invention is to provide a novel and improved toilet seat cover dispenser, which may be coin-controlled, so that upon deposit of a coin of predetermined denomination, the locking means is released for pulling out one seat cover, after which it is again automatically returned to locked position.

A further object of the invention is to provide a novel and improved toilet seat cover dispenser, which is simple in design, inexpensive to manufacture, which is highly sanitary and protective of health, and which may be

2

made of a variety of materials, such as wood, metal, plastic, or a combination of such materials.

These and other objects and advantages of the invention will become apparent from the following description of a preferred embodiment thereof, as illustrated in the accompanying drawings, forming a part hereof, and in which,

Figure 1 is a perspective view showing a toilet or water closet, with my improved seat cover dispensing device mounted adjacent thereto.

Figure 2 is a front elevational view of the device shown in Figure 1.

Figure 3 is a left end elevational view of the device shown in Figure 2, with a portion of a seat cover partly pulled out therefrom, and indicating in broken lines, the opening motion of the cover member.

Figure 4 is a longitudinal sectional elevational view taken substantially on plane 4—4 of Figure 3, a roll of seat covers being shown in position therein, and indicating in broken lines, an outer positioning of the control knob for release of a cover.

Figure 5 is a transverse sectional elevational view taken substantially on plane 5—5 of Figure 4.

Figure 6 is a top plan view of the device shown in Figure 1, apart from the toilet itself, and showing more than one seat cover pulled out from the dispensing housing.

Figure 7 is a top plan view showing another form of the invention, in which the dispensing housing is mounted at the rear of the toilet seat, for being dispensed in a forward direction instead of from the side as shown in Figure 6.

Figure 8 is a fragmentary sectional elevational view taken on a plane similar to that of Figure 4, and showing one mode of tight engagement of the shaft with the roll of toilet seat covers, the view being on an enlarged scale.

In connection with the use of sanitary devices, such as toilets, water closets and the like, the utmost of protection against transmission of disease is needed, and the present invention provides means whereby the cover of the seat of the toilet is covered, and thus there is no possibility of transmission of disease to the user. My improved device includes a main housing within which there is a means for carrying a roll of toilet seat covers, with means for allowing them to be dispensed one by one as needed, and to block dispensing when not desired. Coin controlled locking means may also be provided so that only when a coin is deposited, is it possible to dispense one seat cover. The covers being disposable, and inexpensive, are thus used without any problems at all.

In order to understand clearly the nature of the invention, and the best means for carrying it out, reference may now be had to the drawings, in which like numerals denote similar parts throughout the several views.

As shown, there is a bathroom 10, with a toilet bowl 12 the base 14 of which is supported upon the floor 16 of the bathroom. A toilet seat 18 is hinged at 20 to the rearward portion of the toilet bowl in any suitable manner, and is provided with toilet seat opening 22. The toilet may be provided with a means for flushing the same, such as a low flush tank 24 mounted upon the rear platform 26 of the toilet bowl.

The flush tank is shown for illustrative purposes only as one form of flushing apparatus, but may be omitted in many installations.

In order to provide a sanitary covering for the toilet seat when in use, I provide a dispensing main housing or the like 30, which includes a floor wall 32 secured to left and right end walls 34 and 36, and to front and

rear walls 38 and 40. These walls thus combined to define a main chamber 42 which takes up substantially the entire interior of the main housing in the form illustrated. A roof wall 44 is secured to the upper edges of the walls 34 and 36 and the rearward wall 40, said walls being somewhat inclined at their upper edges to allow the roof wall 44 to be also inclined, as seen in the views.

To form a cover or closure member 46, I form cuts along cut lines 50 in the right and left end walls 34 and 36, which are somewhat more inclined than the inclination of the roof member wall 44, and also make a cut along line 52 in rear wall 40 as shown. Since the front wall 38 only extends upwardly to location 54, it is seen that when a hinge 58 is placed on both sides of the cut line 52 in rear wall 40, a closure member 46 is formed, which is hinged at 58, and is swingable as at 44a upwardly to open the interior of the housing 30. While the hinges 58 are located at the rear of the housing, it will be understood that such hingeing may also be accomplished elsewhere, as when the housing 30 is mounted right against a wall so as to block such ready upturning of the cover. In such event, the hinges may be placed at one end of the housing, which will be modified to make this possible, or right at the top left corner of the roof member 44 as seen in Figure 3, instead of theretofore, the hinges being located at the top left corner of the roof member 44 in such event.

A main roller shaft 60 is reduced at its ends 62 and 64, to allow them to extend through the bearing openings 66 and 68 formed through the end walls 34 and 36 of the main housing, so as to turn freely therein. An inclined access slot 70 may be formed through wall 34 above and communicating with bearing opening 66, to allow the main roller shaft 60 to be inserted and removed when the top cover 46 is uplifted, the slot 70 extending to cut line 50 as seen best in Figures 3 and 4.

The main roller shaft 60 is itself made sufficiently large in diameter intermediate its reduced ends 62 and 64, as to fit snugly inside the hollow tubular hub 72 on which the roll of toilet seat cover members 74 is carried, so that the main roller shaft 60 turns with the roll of toilet seat covers 74, and when the main roller shaft 60 is blocked against turning, then the roll of toilet seat covers 74 cannot turn either. This snug fit may also be achieved by shaping the roller shaft 60 with serrations, ribs or corners for good engagement with the paper hub 72.

A brake or detent wheel or disc 80 is mounted on the rightward end 64 of the main roller shaft 60, for turning therewith, being keyed thereto as shown in Figure 5. The disc 80 has a number of detent holes 82 formed around its marginal perimeter, therethrough, to receive a detent plunger shaft 84 mounted slidably in an opening 86 formed through wall 36 of the main housing. A spring 88 biases the collar 90 on the shaft 84, and hence the shaft 84 itself which is movable with collar 90, leftwardly, as seen in Figure 4, for engagement in any of the holes 82 with which it is brought into registry, thus blocking further turning of the disc 80 and hence of the seat cover roll 74. A pull knob 94 can be pulled to the right, as seen in Figure 4, to allow the detent disc 80 to turn freely, while a seat cover is pulled out, and then is automatically restored to locked position when released, blocking further dispensing or wasting of seat covers.

A guiding roller 100 is mounted at the upper edge 54 of the front lower wall 38, as seen in Figure 5, to allow the seat covers to be pulled out easily. A front closure wall 102 which may be of metal, plastic, clear or transparent plastic, glass or the like, is slidably disposed in grooves 104 formed in the edges of the front wall opening, that is to say, in the front margins of the side or end walls 34 and 36, to allow it to be slidably moved vertically to closed position or opened up. The wall 102

5 has a top flange 106, overlying roof 44, and a lower outstanding flange 108 to facilitate tearing off a single seat cover along its scored tear lines 110. Figure 6 shows how each seat cover section 74 between score lines, has an opening 116 formed therein to overlie the opening in the toilet seat when placed thereon after being torn off. Figure 7 shows how the orientation of the openings is changed when at rear of toilet. In this form, the main housing 30a may be mounted at the rear of the toilet bowl just forwardly or below the flush tank 24a, which may be forwardly recessed as at 25a, to more easily receive the housing 30a.

Referring now to Figure 8, it is seen that here is a further modification of the invention, in showing means for enhancing the grip of the shaft 60a on the roll 74 of toilet seat covers. Here it is seen that the shaft 60a extends through the hollow tubular hub or core 72 of the roll of toilet seat covers, 74, and is provided with an axial slot 130 forming bifurcations as shown. The bifurcated portion of the shaft 60a extends inside the tubular core 72 of the toilet seat cover roll 74 leftwardly of apertured wheel 80, which is keyed at 65 to shaft 60a. The spacing collar or washer 132 is disposed to the right of wall 34 of the main housing, and is provided with an opening 134 to receive the bifurcated shaft left end portion 130. The opening 134 has a diametral integral wedge portion 136 extending across it, so as to extend into the slot between the bifurcations of the shaft 60a. The spacing collar or washer 132 is thus carried by the shaft 60a with the central wedge portion 136 between the bifurcations of the shaft 60a. The wedge 136 thus presses the bifurcations apart, and tightly causes them to grip the tubular hub 72 so as to cause the roll 74 and the shaft 60a to surely turn together. The opening 66a in wall 34 is also enlarged to allow the reduced bifurcations to turn freely therein while expanded. Sufficient clearance or play is left in the various parts as seen in Figure 8, to allow easy insertion and removal with the aid of slot 70 also.

40 Although I have described my invention in specific terms, it will be understood that various changes may be made in size, shape, materials and arrangement without departing from the spirit and scope of the invention as claimed.

45 I claim:

A toilet seat cover dispenser comprising a main housing defining a chamber, a main unbiased shaft journaled in said chamber, and construction and arranged for supporting a roll of toilet seat covers, said chamber having 50 a discharge outlet for outlet of said seat covers one by one, cutting means at said discharge outlet and substantially spaced from the outer surface thereof, for cutting off a seat cover at a time from said roll, and so that when said cover is severed, a substantial leading marginal edge portion of the next unsevered seat cover extends outwardly from said chamber for being grasped by hand when another seat cover is to be dispensed, detent means 55 constructed and arranged for blocking turning of said roll of toilet seat covers, spring means for biasing said detent means into extended blocking position, said detent means being constructed and arranged for being moved by hand to retracted unblocking position as needed, to allow dispensing of a seat cover, and wherein there is an apertured wheel carried on said main shaft for turning therewith, said roll of toilet seat covers comprising a continuous series of interconnected toilet seat covers in sheet form wound around a tubular hollow core member hub, said main shaft being bifurcated where it extends through said seat cover roll hub, wedge means constructed and 60 arranged for extending into the space between said bifurcations to expand them to tightly engage against said toilet seat cover roll hub, to secure said hub for turning with said shaft, said detent means comprising a spring 65 pressed detent rod which when extended engages in an aperture of said apertured wheel to block turning thereof.

and of said seat cover roll, and when pulled to retracted position disengages therewith, allowing dispensing of a seat cover.
